(57) **CLAIM**

The ornamental design for a clothing hanger accessory, as shown and described.

DESCRIPTION

FIG. 1 is a top front perspective view of a clothing hanger accessory shown in an alternate configuration and in environmental use;

FIG. 2 is a top front perspective view of the clothing hanger accessory;

FIG. 3 is a front elevation view of the clothing hanger accessory;

FIG. 4 is a rear elevation view of the clothing hanger accessory;

FIG. 5 is a left elevation view of the clothing hanger accessory;

FIG. 6 is a right elevation view of the clothing hanger accessory;

FIG. 7 is a top plan view of the clothing hanger accessory; and,

FIG. 8 is a bottom plan view of the clothing hanger accessory. The broken lines shown represent unclaimed subject matter and form no part of the claimed design.
